UNITED STATES PATENT OFFICE.

ARNOLD S. BREAKEY, OF EAST ORANGE, NEW JERSEY, AND CHARLES F. PIETSCH, OF MALVERN, NEW YORK.

SAFETY RAZOR.

Application filed February 2, 1921. Serial No. 441,883.

To all whom it may concern:

Be it known that we, ARNOLD STEWART BREAKEY and CHARLES FRANCIS PIETSCH, both citizens of the United States, and residents of East Orange, in the county of Essex and State of New Jersey, and Malvern, in the county of Nassau, Long Island, and State of New York, respectively, have invented certain new and useful Improvements in Safety Razors, of which the following is a full, clear, and exact description.

Our invention relates to a safety razor and aims to provide certain new and useful improvements in devices of this character.

It is well appreciated in connection with safety razors that most of the same include a head provided with a blade seat and clamping member between which elements the 20 blade is interposed. A suitable handle is provided in association with the head and suitable means is also provided for retaining the whole in applied position.

These devices have further offered objections in that it has been incumbent upon a person to utilize the same for a certain length of time before a proper manipulation of the razor would be accomplished in that a person utilizing this device would 30 not hold the handle, and consequently the head of the razor at the proper angle to the surface to be shaved, thus producing unsatisfactory results.

A further defect was to be attributed to the fact that it was necessary, subsequent to the shaving operation, to disassemble all of the parts of the razor to permit of the removal of the clamping member, the blade and handle, so that these parts might be 40 cleaned to guard against the accumulation of soap, skin and hair, aside from the fact that any particles of moisture would form rust.

With this in view, we have constructed a safety razor by means of which, primarily, a razor is provided, which will permit of an inexperienced operator manipulating the same to produce the most desired results.

A further object of our invention is the provision of a safety razor, the parts of which may be readily cleaned without resorting to disassembling, thus avoiding the difficulty incident to this feature.

Reference is had to the attached sheet of drawings as illustrating one practical em-

bodiment of our invention, and in which:

Figure 1 is a perspective view of a razor constructed in accordance with our invention.

Figure 2 is a plan view of the same.

Figure 3 is a sectional view taken along the line 3—3 of Figure 2 in the direction of the arrows.

In these views the reference numeral 5 indicates the conventional blade seat of the head, from which the handle 6 extends, and upon which the blade 7 is positioned. Also as in the conventional construction, the side edges of the blade seat 5 are provided with serrations or teeth 8, and a stem (not shown) 70 is positioned within the handle 6 and may be turned, by a knurled portion 9 to force the blade clamping member into more intimate engagement with the seat 5.

Contrary to the conventional construction, however, it will be noted that this member bears against the seat 5 only adjacent its side edges 10, and that the center portion 11 of the same is bowed upwardly, as has been illustrated in Figures 1 and 3. 80 Also the guide pins 12 which are associated with the clamping member 11 for retaining the same in proper position, are preferably formed with collars or enlarged portions 13 upon their bodies, which collars 85 bear against the upper face of the blade 7.

Thus upon the blade 7 being properly interposed between the blade seat 5 of the clamping portion of the head, and the stem portion, by the knurled portion 9 to properly seat these members, that the blade will be pressed into intimate engagement with the seat 5, and the guide pins 12 projecting through openings in the blade and seat 5 in the usual manner, will serve to retain the 95 whole in applied position.

Also it will be seen that contrary to the conventional construction, which provides straight side edges for the clamping member, that these edges are serrated or provided with teeth 14 so that contact between the blades 7 and the clamping member will be reduced to a minimum, at which the result desired may be effectively achieved.

From the foregoing it will be seen, referring primarily to the body portion 11 of the clamping member, that the same will serve as a guide, reference being had to Figure 3, which co-operating with the serrations 8 of the blade seat 5 will permit a 110

novice to at all times hold the head of the razor at an angle at which it will operate with a maximum of efficiency.

It will also be appreciated that by virtue 5 of this body portion, and the serrations 14, that the entire razor may be placed under flowing water which will serve to remove all foreign particles, and by virtue of the fact that no pockets, permitting of the 10 seclusion of moisture, are permitted by this construction, that the operator may remove all moisture from within the body of the razor by resorting to brisk shaking of the same, thus the necessity of disassembling 15 the razor to permit of its cleansing is eliminated.

Thus it will be appreciated that we have constructed a razor which provides certain improvements over certain razors heretofore 20 placed upon the market, in that it permits an inexperienced operator to manipulate the same properly, aside from the fact that it will not be necessary to take the razor apart to cleanse the same.

Obviously numerous modifications of structure might readily be resorted to without in the least departing from the scope of our claim, which is—

A safety razor including a plate-seat, a plate depressor, and means for retaining said plate depressor against said seat, said plate depressor having its body bowed upwardly at a point substantially intermediate its side edges whereby to provide a guide portion adapted to co-act with the surface being shaved the under face of said plate depressor being spaced from the upper face of said seat at this point, guide pins secured to the under face of said depressor and adjacent the center portion thereof, said guide pins being adapted to extend into openings formed in said seat, and collars associated with said guide pins and positioned in such a manner as to normally lie adjacent the upper face of said seat.

ARNOLD S. BREAKEY.
CHARLES F. PIETSCH.
